UNITED STATES PATENT OFFICE.

GEORGE LEROY MILLER, OF SHICKSHINNY, PENNSYLVANIA.

VALVE PLUNGER.

Application filed February 20, 1924. Serial No. 694,101.

To all whom it may concern:

Be it known that I, GEORGE L. MILLER, a citizen of the United States, residing at Shickshinny, in the county of Luzerne and State of Pennsylvania, have invented a new and useful Valve Plunger, of which the following is a specification.

This invention relates to a valve plunger, especially adapted for use in jigs of the 10 type described in my companion application, Serial Number 694,100, filed of even date herewith. Jigs of this type are used in separating coal and other substances from waste matter associated therewith, by the 15 utilization of the differences in their specific gravities.

The general object of the present invention is to insure a steady and uniform flow of water through the jig of sufficient volume 20 and velocity to hold the particles of coal practically in a state of suspension, while the heavier particles of slate or other refuse are separated therefrom, and allowed to settle in the bottom of the separator box 25 from which they are subsequently discharged.

One of the specific objects of the invention is to provide improved means particularly adapted for use in a plunger of comparatively large size and rectangular in shape, whereby a close contact is insured with the side walls of the chamber in which it operates, so that leakage is prevented and a high efficiency obtained.

35 A further object of the invention is to provide an improved arrangement of ports through the plunger and of the valves cooperating with the same, whereby the flow of water is rendered steadier, and the volume of the flow is increased.

With the above and other objects in view, the invention consists in various details of construction and combinations of elements which will be more particularly explained 45 in the following detailed description, which is to be read in connection with the accompanying drawings illustrating the invention in its preferred form.

In the drawings:

50 Figure 1 is a vertical sectional view of a portion of a jig with my improved plunger shown in connection therewith.

Figure 2 is a horizontal section through the upper part of the plunger.

Figure 3 is a vertical section taken on 55 the line 3—3 of Figure 2.

Figure 4 is a side elevation of the plunger with a part thereof shown in section.

Figure 5 is a detail perspective view showing the relation of the plunger shoes. 60

The invention is illustrated in the accompanying drawings in connection with a jig comprising a suitable frame 10, in which is supported a tank 11 containing a separator box 12, into which the coal to be separated is introduced by means of a suitable chute 13. The tank also contains a chamber 14, in which the plunger 15 is adapted to reciprocate to cause a circulation of the water in the tank downwardly through the chamber 14, and laterally through a valved partition 16, whence the water passes upwardly through the inclined perforated bottom 17 of the separator box 12, from which it is discharged laterally and returns to the upper part of the chamber 14 through an opening 18 cut out of the upper part of the side wall of the chamber. 70

The plunger 15 is carried at the lower end of a pair of spaced pitman bars 19, which are journaled at their upper ends on eccentricities 20, secured to a shaft 21 journaled in the frame 10 directly above the chamber 14, and rotated by a pulley wheel 22, or other suitable means to cause a vertical reciprocation of the plunger 15. The chamber 14 is necessarily of considerable size, and is ordinarily made of rectangular shape. The plunger is of similar size and shape, and includes a casting in the form of a rectangular skeleton frame 23, having midway thereof a transverse double web portion 24 forming a channel, which is closed at each end by upwardly extending ends 25, forming sockets in which the lower ends of the pitman bars 19 are seated. The bars 19 are firmly secured to the ends 25 by means of bolts 26, and the inner faces of the ends 25 are preferably formed with spurs 27 which bite into the bars 19, which are usually of wood, and assist in securing the plunger 80

against longitudinal play with respect to the pitman bars. The sides 24 of the transverse double web portion are strengthened by 90 long 95

100

itudinal web portions 28, which are extended along the sides of the plunger to form reinforcing ribs. The faces of the plunger at each side of the transverse web 24 is in the form of a rectangular plate 29, integrally connected to the frame 23 by narrow strips 30, which define relatively large openings 31, constituting ports through which the water may pass.

10 The passage of water through the ports 31 is controlled by check valves 32, one of which is provided for each half of the plunger. Each of the check valves 32 is rectangular in shape, and is mounted at its corners on bolts 33 which are secured to the corners of the frame 23, and are slideable on sleeves 34 which surround the respective bolts. Ex-pansile coiled springs 35, surrounding the sleeves 34, urge the valves 32 toward the 20 face of the plunger, but permit the valves to open during the upward stroke of the plunger. The valves are provided with central rectangular openings 36 corresponding to the plates 27, while the solid portions of 25 the valves are adapted to cover the ports 31. The transverse web portions 24 are provided with openings 37 of considerable size, so as to permit free circulation between opposite ends of the plunger, and to equalize the pressure of the water thereon.

30 The partition 16 consists of a skeleton framework and central plate 38, similar to the frame 23 and plate 29 of the plunger, and the passage of water therethrough is controlled by a check valve 39, similar to the valves 32. Thus, it will be understood that during the down stroke of the plunger the valves 32 are closed, while the valve 39 is opened, and during the upward stroke of 40 the plunger the valve 39 closes while the valves 32 open.

45 In order to insure a close engagement of the sides of the plunger against the walls of the chamber 14, the sides of the plunger are provided with shoes 40, which have the same function as the piston rings on a cylindrical piston. Each of these shoes 40 is channel shaped, and fits over the edge of the frame 23, and is urged outwardly into engagement 50 with the wall of the chamber by a bowed leaf spring 41, which is held between the bottom of the channel and the edge of the plunger arm. At the corners of the plunger frame, the ends of the shoes 40 are rabbeted, 55 as shown at 42, so as to overlap and to form a seal, which is practically continuous throughout the periphery of the plunger. Each spring 41 exerts pressure against both ends of the shoe within which it is held, so 60 that the pressure is equalized throughout the length of the shoe. On account of the large size of the plunger and the difficulty which would otherwise be experienced in assembling the same within the chamber 14, it is 65 preferable to provide holes 43 through the

frame 23 near the edge thereof, and to provide corresponding holes 44 through the flanges of the shoes 40. When the plunger is in active position, the holes 44 will usually be outside of the holes 43, but in assembling, 70 the shoes may be forced inwardly against the pressure of the springs 41, so that the holes 44 and 43 will be in registry, and pins may be inserted therethrough to hold the shoes in contracted position, thus permitting the 75 plunger to be easily inserted into the chamber, after which the pins may be withdrawn leaving the plunger in operative position.

The sides of the tank 11 and three sides of the chamber 14 are usually constructed of 80 wood, while the partition 45, between the chamber 14 and the separator box 12, is usually of metal. A suitable wear plate 46 is, therefore, secured to the wooden sides of the chamber 14 to provide a suitable wearing 85 surface against which the shoes 40 may reciprocate.

In the operation of the jig the reciprocation of plunger is quite rapid, but its amplitude is small, so that the flow of water is 90 substantially continuous. The valves 32 and 39 are quickly responsive to the movement of the plunger, so that just as soon as the plunger reaches the lowest point in its movement and starts its upward movement, the 95 valve 39 quickly closes and water passes downwardly through the valves 32 during the upward stroke. At the beginning of the down stroke, the valves 32 close just as quickly, and the water is forced through the 100 ports in the partition 16. The engagement of the shoes 40 with the sides of the chamber substantially prevent any leakage around the sides of the plunger, thus insuring the highest efficiency. The skeleton structure of 105 the plunger and the partition 16 provides ports, which constitute substantially half of the area of the frame, so that the maximum flow of water through the ports is obtained. The plunger, therefore, meets with very little 110 resistance from the inertia of the water, and it is possible, therefore, to operate the plunger rapidly and with comparatively little power, so that a very economical operation of the jig is insured.

115 While I have shown and described specifically the preferred structure by means of which the invention may be embodied, it is to be understood that this is merely for the purpose of illustration, and that the invention is not limited thereto, but that various modifications may be made therein without departing from the salient features of the invention as herein claimed.

120 What is claimed is:

1. In a device of the character described, the combination of a rectangular chamber, a plunger having a head conforming to the sides of the chamber and reciprocable therein, channel shaped shoes embracing the sides 125

of the plunger and slidably supported thereon, and springs seated between the bottoms of the channels and the sides of the plunger and urging said shoes into close contact 5 with the sides of the chamber.

2. In a device of the character described, the combination of a rectangular chamber, a plunger having a head conforming to the sides of the chamber and reciprocable 10 therein, channel shaped shoes embracing the sides of the plunger and slidably supported thereon, and bowed leaf springs seated against the sides of the plunger with the ends of the springs engaging the bottoms 15 of the channels near the ends thereof, and urging both ends of the respective shoes into close contact with the sides of the chamber, the side flanges of said shoes having holes therethrough adapted to register with 20 the holes through the head when the shoes are pressed inwardly against the resistance of the springs, whereby pins may be inserted to retain the shoes in that position while the plunger is being assembled.

3. In a device of the character described, 25 the combination of a plunger having a rectangular head, channel shaped shoes embracing the sides of the head and slidably supported thereon, springs seated between the bottoms of the channels and the sides 30 of the head and urging said shoes outwardly, each of said shoes having rabbeted ends which overlap the ends of the adjacent shoes, so that the plunger forms a substantially continuous contact with the walls of the chamber within which it operates.

4. In a device of the character described, 35 the combination of a rectangular chamber, a plunger having a head conforming to the sides of the chamber and reciprocable therein, said head having a plurality of holes through each side near its periphery, channel shaped shoes embracing the sides of the plunger and slidably supported thereon and covering said holes, and springs seated between the bottoms of the channels and the sides 40 of the plunger and urging the plunger into close contact with the sides of the chamber, the side flanges of said shoes having holes therethrough adapted to register with 45 the holes in the head when the shoes are pressed inwardly against the resistance of the springs, whereby pins may be inserted to retain the shoes in that position while the plunger is being assembled.

5. In a device of the character described, 50 the combination of a rectangular chamber, a plunger having a head conforming to the sides of the chamber and reciprocable there-

in, said head having a plurality of holes through each side near its periphery, channel shaped shoes embracing the sides of the plunger and slidably supported thereon and covering said holes, and bowed leaf springs seated against the sides of the plunger with the ends of the springs engaging the bottoms of the channels near the ends thereof, and urging both ends of the respective shoes into close contact with the sides of the chamber, the side flanges of said shoes having holes therethrough adapted to register with 60 the holes through the head when the shoes are pressed inwardly against the resistance of the springs, whereby pins may be inserted to retain the shoes in that position while the plunger is being assembled.

6. In a device of the character described, 65 the combination of a rectangular chamber, a plunger having a rectangular head conforming to the sides of the chamber and reciprocable therein, said head being formed 70 by a skeleton frame with a central plate integrally connected to the rim of the frame by narrow strips leaving ports of comparatively large area, and a spring held reciprocatory valve in the shape of a hollow rectangular plate normally covering said ports.

7. In a device of the character described, 75 the combination of a rectangular chamber, a plunger having a head conforming to the sides of the chamber and formed by a skeleton 80 frame with a central plate integrally connected to the rim of the frame by narrow strips leaving ports of comparatively large area, a spring held reciprocatory valve 85 in the shape of a hollow rectangular plate normally covering said ports when the plunger is moved in one direction, but adapted to open against the resistance of the springs when the plunger is moved in the opposite direction, channel shaped shoes 90 embracing the side edges of said frame and slidably supported thereon, and springs seated between the bottoms of the channels and the sides 95 of the plunger and urging said shoes into close contact with the sides 100 of the chamber.

In testimony, that I claim the foregoing as my own, I have hereto affixed my signature.

GEORGE LEROY MILLER.
